Primary Examiner — Barbara Fox*Assistant Examiner* — Messina L Smith(74) *Attorney, Agent, or Firm* — Kile Park Reed & Houtteman PLLC(57) **CLAIM**

I claim, the ornamental design for an infrared heating cooker, as shown and described.

DESCRIPTION

FIG. 1 is a top and front perspective view of an infrared heating cooker, showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a reference view showing a use of the infrared heating cooker to which a detachable cooking pan is attached; and,

FIG. 9 is an enlarged view of a portion of the infrared heating cooker shown in FIG. 2.

The broken line showing of the tray in FIG. 8 depicts environment and forms no part of the claimed design.
